2 Sheets-Sheet 2

UNITED STATES PATENT OFFICE.

GEORGE A. SUITS, OF MEDFORD, MASSACHUSETTS.

POLISHING DEVICE.

Application filed July 9, 1928. Serial No. 291,277.

The object of this invention is the provision of a shoe polishing device, primarily designed for use in hotels or in other public places, but, of course, susceptible for employment in other connections and the primary object is the provision of a motor driven brush which is hitched with the house current, the circuit of which being controlled by a novel circuit maker, so that 10 the same is open when the foot supporting lid of the improvement is in closed position and closed when the foot supporting lid is moved to open position so that the brush will be thus revolved and brush and polish the 15 shoe of the user.

The invention will be fully and comprehensively understood from a consideration of the following detailed description when read in connection with the accompanying 20 drawings which form part of the application, with the understanding, however, that the improvement is capable of extended application and is not confined to the exact showing of the drawings nor to the precise 25 construction described and, therefore, such changes and modifications may be made therefrom as do not affect the spirit of the invention nor exceed the scope thereof as expressed in the appended claim.

30 In the drawings:

Figure 1 is a front elevation of my improvement showing the same in operative position, parts being broken away and parts in section, and also the front plate being removed.

Figure 2 is a horizontal sectional view approximately on the line 2—2 of Figure 1.

Figure 3 is a transverse sectional view on the line 3—3 of Figure 1.

Figure 4 is a similar sectional view but showing the front closed and the circuit for the motor broken.

Figure 5 is a perspective view of the improvement with the parts arranged as disclosed in Figures 1, 2 and 3.

Figure 6 is a sectional view approximately on the line 6—6 of Figure 1, but showing the arrangement of the post when the door is closed.

50 In the showing of the drawings I have disclosed my improvement arranged in a suitable pocket in a wall directly above the base board thereof. This is desirable when the device is employed in hotels or like public places, but obviously the improvement

may be of a portable nature and may be employed in a household or in any other desired place. In the showing of the drawings, the improvement contemplates the employment of a metal box-like casing 1. The 60 wall provided by the opening in which the casing is locked has arranged thereon a frame tool in the nature of plates 2 which are disposed over the top and side edges of the casing 1.

Preferably the front of the casing is wholly open, and the sides at a suitable distance below the top thereof have secured thereon angle cleats 3 on which rests and is preferably secured a shelf 4. The shelf divides 70 the casing into an upper compartment 5 and into a lower compartment 6. The shelf supports thereon a motor 7 to which is connected one of the conductor wires 8 that leads to an insulating sleeve 9 in the top of 75 the casing. When the device is portable the conductors for the motor have their outer ends attached to a suitable plug to be received in a wall socket of the house circuit. The second wire leading from the motor is 80 indicated by the numeral 10, and this wire is secured to a terminal or contact 11 that is adjustably mounted on a post 12 which has one of its ends received in the socket of an insulating block 13 that is fixed on the shelf 85 4. The post 12 is screwed in the tubular end of a cross sectionally rounded rod 14 that passes through the lower end of the block 13 and through a suitable opening in the shelf. The contact 11 is designed to engage with 90 the second contact 16 fixed on an upstanding arm whose angle end is secured on the block 13 and to which end there is connected the terminal of an encased wire 17 that in turn is connected to a fuse or like emergency 95 cutout 19 that is supported on the shelf. The return wire of the circuit is indicated for distinction by the numeral 20 and, of course, leads from the emergency cutout 19.

Fixed on the motor shaft 21 there is a 100 sprocket wheel that has trained therearound an endless sprocket chain 22. The sprocket chain is also trained around a larger sprocket wheel on the shaft or trunnion 23 on one end of the core of a fibre or bristle brush 24. The second trunnion for the core of the brush 24 is indicated by the numeral 25, and both of the trunnions 23 and 25 are journaled in suitable bearings 26 provided on the ends of hangers that are secured to 110

the under face of the shelf 4. Of course, the chain 22 passes through a suitable opening in the shelf 4. Secured to the under face of the shelf, preferably by the means 26' that attach the insulator block 13 thereto there is a substantially U-shaped guide member or bracket 27 through which passes one end of a post 28. The post is preferably of insulating material and has fixed on its upper end a head 29 that contacts with the outer or lower end of the element 14. The outer end of the post 28 is received in a suitable opening 29' in the bottom of the casing 1. The door or closure 30 is hinged 15 to the bottom of the casing 1 and the hinges 31 are spring influenced whereby the door is normally swung to closed position. By reference to the drawings it will be seen that the door is of a materially less 20 width than the open face of the casing 1, and, therefore, I removably secure in the said open face of the casing 1 a closure plate 32. The door may abut against the lower edge of this plate when in closed position. The door or closure 30 has fixed 25 on its inner face a bracket to which is pivotally secured one end of a bar or plate 33. This plate is provided with an elongated slot 34 that merges into an angle slot 35 and 30 there is fixed on one side of the casing 1 the shank of a headed element 36 that passes through the slot 34, and when the door or closure is in open position is received in the lateral passage 35 of the said slot 34 and 35 whereby the door or closure is held in open position. The rod 28 is designed to pass freely through the opening 29', the said opening being preferably surrounded by a guide flange as disclosed by the drawings 40 and the lower end of the rod 28 is in the path of contact with the straight end of an offset plate 37, one end of which being fixed, as at 38, to the inner face of the door or closure 30. The shoulder 29 on the rod 28 limits the downward gravitation of the said rod through the opening 29' as the shoulders will contact with the horizontal 45 wall of the substantially U-shaped bracket 27. The element 14, carrying the contact 11 is of sufficient weight to gravitate with the rod 28, but in the socket provided in the block 13 for the rod 12 there is arranged a coil spring 39 which exerts a pressure between the upper and inner wall of the said socket and the inner end of the element 14, which influences the contact 11 away from the contact 16. Thus it will be noted that the circuit for the motor is normally open. The door or closure 30 is provided with a handle 40 on its outer face and may be likewise provided with suitable latching means. It will be obvious that on

swinging of the door to horizontal position, as disclosed by Figures 1 and 2 of the drawings, the lower face of the shoulder will contact with the molding 41 for the base board of the room in which the device is arranged. In addition to this the outward swinging of the door causes the element 36 which is received in the lateral passage 35 of the slot 34 and the stop plate or arm 37 to limit such outward swinging of the door or closure. 65 70

When the door or closure is swung to horizontal position it will be apparent that the plate 37 will exert an upward push upon the rod 28, causing the latter to have its head 29 brought against the lower end of the element 14, thereby moving the rod 12 so that the contact 11 thereon is brought against the contact 16 so that the circuit is 75 completed and the cylindrical brush 24 is 80 rotated. The distance between the closure 30 and the brush is sufficient for the operator to place his shoe at desired angles into the receptacle 1, so that all parts of his shoe 85 will be effectively cleaned by the rotating brush 24. By simply closing the door or closure 30 the circuit is automatically broken.

My improvement is of an extremely simple construction and the advantages thereof will, it is thought, be perfectly understood by those skilled in the art to which such invention relates.

Having described the invention, I claim: 95
A shoe polishing device including a casing, having a horizontal shelf therein dividing the same into an upper and into a lower compartment, a motor in the upper compartment, a normally open circuit for 100 the motor, spaced contacts on the terminals of the circuit, one of said contacts being spring influenced away from the other, a rotary brush having trunnions journaled in the lower compartment, an endless chain 105 trained around the motor shaft and a trunnion for the brush, a substantially U-shaped bracket on the under face of the partition, a rod movable therethrough and in the path of engagement with the spring influenced 110 contact, a head on the rod for preventing the movement thereof through the bracket, said rod being movable through an opening in the bottom of the casing, a plate for closing the upper compartment, a spring hinged door for closing the lower compartment, and said door providing a foot rest when in open position, and a plate on the door 115 engaging with the lower end of the rod for moving the same upwardly and for closing the circuit when the door is in open position.

In testimony whereof I affix my signature.

GEORGE A. SUITS.
